UNITED STATES PATENT OFFICE.

PETER C. KANE, OF YOUNGSTOWN, OHIO.

ANTISKIDDING DEVICE.

1,356,288.

Specification of Letters Patent.

Patented Oct. 19, 1920.

Application filed April 13, 1920. Serial No. 373,534.

To all whom it may concern:

Be it known that I, PETER C. KANE, a citizen of the United States of America, residing at Youngstown, in the county of 5 Mahoning and State of Ohio, have invented certain new and useful Improvements in Antiskidding Devices, of which the following is a specification.

This invention relates to antiskidding devices for auto tires and protection for the same against rapid and excessive wear, and also against puncture.

The principal object is to provide a device which will function as above stated and still allow desired resiliency of the tire. In order to do this I have provided four equal armor sections carrying suitable cleats.

Another object of my invention is to provide an antiskidding device of the character described, which is simple as to construction, reliable and efficient in operation, capable of being readily attached and detached and which is cheap to manufacture.

25 The above and additional objects are accomplished by such means as are illustrated in the accompanying drawings, described in the following specification, and then more particularly pointed out as claimed.

30 With reference to the drawings wherein I have illustrated the preferred embodiment of my invention as it is reduced to practice, and throughout the several views of which similar reference members designate 35 corresponding parts, Figure 1 is a side elevation of the device when attached. Fig. 2 is a detailed top plan view showing the position of lugs and interlocking tongue. Fig. 3 is a cross section through the device, 40 tire, rim and felly, taken on line A—A of Fig. 1.

The improved device is composed of four equal and similar armor sections 1. Each of said armor sections 1 is provided with 45 a tongue 2 formed at one end of said armor section 1, and projecting underneath an adjacent end of a companion armor section 1, thereby interlocking the sections above mentioned.

50 By referring to Figs. 1 and 2 it will be seen that I have provided inwardly extend-

ing portions 3 provided with outturned lips 4.

The armor sections 1 have a short extension over the tread and terminate at the 55 bolt 5.

One of the means for holding the armor sections 1 in position comprises bolts 5 which pass through any suitable openings at 60 points 6 and 7 in the armor sections 1.

By referring to Fig. 1 it will be seen that the lips 4 are diametrically opposite each other, and similarly positioned are slotted openings 8 through which pass the bolts 9. These bolts 9 aid in holding the armor sections 1 in position, and also allow for certain resiliency, for when the weight is upon any part of one of the armor sections 1, there will be a certain depression of the armor section 1 toward the center of wheel, 70 causing the lips 4 in turn to slide upon the bolts.

By referring to Figs. 1 and 2 it will be seen that I have provided cleats 10 securely attached to the armor sections 1 by any suitable means and extending across the tread of the armor sections 1. It will also be seen that I have provided cleats 11 secured to the tread of the armor sections 1 and running lengthwise with the tread. In 80 order to secure their proper contact with the surface upon which the wheel is traveling when subjected to a tendency to skid I have positioned the cleats 11 in staggered arrangement as will be seen by referring to 85 Figs. 1 and 2. These cleats 11 may be of suitable length in order to efficiently function.

What I claim is:

1. In a device of the class described, a 90 plurality of the armor sections, cleats secured to the tread of same, cleats secured to the tread in staggered arrangement, inwardly extended parts of said sections, outwardly turned lips on each of said inwardly 95 extended parts of said sections, slotted openings in said lips, and means for securing said inwardly extended parts of said sections, substantially as described for the purpose set forth.

2. In a device of the class described, the combination of a plurality of armor sec-

tions, each section provided with a tongue at one end thereof interlocking with the corresponding end of the adjacent section; inwardly extended parts of said sections, 5 outwardly extended lips formed on said parts, slotted openings in said lips, securing means registering with said slotted openings, securing means whereby the outer and inner downwardly extended parts of the armor sections are secured without contact 10

with tire, rim, or felly, cleats in staggered arrangement and secured to the edges of the tread portion of the armor sections, substantially as described for the purpose set forth.

15

In testimony whereof I affix my signature.

PETER C. KANE.

Witnesses:

FRANK C. JACKSON,
C. A. HARPMAN.
